TRANSFORMER

Filed May 27, 1924

FIG. 1.

FIG. 2.

UNITED STATES PATENT OFFICE.

ERNEST G. DANIELSON, OF SAN FRANCISCO, CALIFORNIA, ASSIGNOR TO E. T. CUNNINGHAM, OF SAN FRANCISCO, CALIFORNIA.

TRANSFORMER.

Application filed May 27, 1924. Serial No. 716,168.

This invention relates to a transformer of high frequency currents, and more particularly to the housing of such coils.

It is one of the objects of my invention to provide a radio frequency transformer that is inexpensive in construction and neat in appearance.

It is another object of my invention to construct a radio frequency transformer with comparatively few parts to assemble, especially as regards the housing or casing.

My invention possesses other advantageous features, some of which, with the foregoing, will be set forth at length in the following description, where I shall outline in full that form of the invention which I have selected for illustration in the drawings accompanying and forming part of the present application. Although I have shown in the drawings but one form of my invention, I do not desire to be limited thereto, since the invention as expressed in the claim may be embodied in other forms also.

Referring to the drawings:

Figure 1 is a main sectional view of a radio frequency transformer embodying my invention; and

Fig. 2 is another sectional view, taken along plane 2-2 of Fig. 1.

In the present instance, the elements of the transformer consist of coaxially arranged coils 11, which may be connected in any appropriate manner to form primary or secondary windings, or even a single winding if desired. A core 12 of magnetic material is disposed so as to extend through all of the coils 11 and independently support the same, and is shown as formed of a bundle of fine wires extending along the length of the coils.

One of the features of my invention resides in the manner in which the core 12 and the coils 11 are supported. A base member 13, preferably of molded insulation material, such as bakelite, has formed integrally therewith, a tube 14 into which the core 12 is placed. The cylindrical base 13 thus serves as a pedestal for a vertically disposed core support, which is coaxial with the base and extends upwardly therefrom. The coils 11 pass over the outside of the tube 14, and are fastened in any appropriate manner there-

on, as by the provision of a snug fit between them, or if necessary by the aid of an adhesive. It must of course be remembered that transformers such as those illustrated are of very small size—comparable with the size of the figures in the drawing—so that no problem exists as regards mechanical stresses or the like. Furthermore, the wire used in coils 11 is of correspondingly fine calibre.

The base 13 is shown in the present instance as circular, although that is not a requisite. In order to reduce the material used for the base, while maintaining it sufficiently rigid, a flange 15 extends upwardly from the base, and a plurality of ribs or vanes 16 connect this flange with the hub part of the base from which the tube 14 extends.

In order to protect the coils and core from foreign matter, as well as to provide a neat appearance to the device, I provide an insulating casing or hood 17 for the transformer. This casing slips over the base 13, as illustrated in Fig. 1, so as to embrace the base quite closely. A square flange 18 or the like permits the provision of several apertures 19 for fastening the entire device to any appropriate support. To maintain the casing 17 in fixed relation to the base 13, any appropriate fastening means may be provided, such as a dowel pin 20 that passes through the wall of casing 17 and engages the base 13. Preferably this casing is also made from insulation material.

The top part of casing 17 has embedded therein the bottom portions of a plurality of metallic binding posts 21. These posts are each provided with a longitudinal aperture 22 in which the leads from the coils 11 may be soldered. Appropriately formed bosses 23 are shown on casing 17 to thicken the material where the binding posts 21 are attached; furthermore, as is usual, washers 24 and thumb nuts 25 are provided for facilitating electrical connection to an external circuit.

The entire coil structure presents a smooth and pleasing appearance, which is due in a great measure to the use of the smoothly rounded casing 17.

I claim:

A transformer having a circular, flanged

base of molded insulation material, a hollow tube coaxial with the base and extending therefrom, said tube being formed integrally with the base, a core located within the tube, the circular base, and telescoping thereover, means for fastening the base and casing together, and binding posts carried by the casing.

5 coils independently supported around the tube, a casing of molded insulation material, a cylindrical inner surface cooperating with

In testimony whereof, I have hereunto set my hand.

ERNEST G. DANIELSON.
